ATTORNEY

UNITED STATES PATENT OFFICE.

BENJAMIN L. DRAPEAU, OF JERSEY CITY, NEW JERSEY, ASSIGNOR TO STANDARD ABRASIVE CO., OF JERSEY CITY, NEW JERSEY, A CORPORATION OF NEW JERSEY.

BOX.

Application filed June 9, 1927. Serial No. 197,683.

The box of the present invention may have a wide range of utility, but is primarily intended for use as a dispensing container and storage container for sheet material, such 5 for instance as sheets of sandpaper.

An object of the invention is to provide a relatively fragile box of this type preferably of light paper or cardboard construction, so reinforced that a number of boxes may be 10 superimposed one upon the other and stored upon a shelf without danger of crushing the boxes.

Another object of the invention is to provide a box so constructed that the sheets of 15 material may be readily manually removed therefrom, thereby providing a convenient readily accessible storage container from which small quantities of the sheets may be withdrawn and sold at retail.

20 Another object of the invention is to provide a box so arranged that a storekeeper will at all times be afforded a visible indication of the number of sheets remaining, so that he will be warned when the stock is running low, or when the box is empty and needs 25 to be discarded.

Other objects of the invention are to provide a box of simple, practical construction which will be rugged, durable and efficient in 30 use, and which is well suited to the requirements of economical manufacture.

With the above noted and other objects in view, the invention consists in certain novel features of construction and combinations 35 and arrangements of parts, as will be more fully hereinafter set forth and pointed out in the claim. The invention may be fully understood from the following description in connection with the accompanying drawings, wherein—

Fig. 1 is a fragmentary perspective view showing the box of the present invention filled with sheet material prior to the dispensing of any of the material.

45 Fig. 2 is a similar view, but showing the front cover flap folded down, and the legend-bearing tab torn from one of the inwardly folding side flaps.

Fig. 3 is a longitudinal sectional detail 50 on the line 3—3 of Fig. 1.

In the drawings I have used the reference numeral 10 to designate a relatively flat box of rectangular shape in cross section preferably formed of relatively thin cardboard or

the like. One end of this box may be temporarily or permanently closed in any convenient or conventional manner (not illustrated), and at the other end of the box there are a pair of side tabs 11 joined to the box body along perforated folding or tearing lines 11^a folding inwardly, an end flap 12 covering the tabs 11, and a flanged portion 13 adapted to be tucked into the box.

An integral bendable tongue 14 cut from the flap 12 provides a convenient handle means for pulling the flap outwardly and downwardly to expose the contents of the box, such for instance as the sandpaper sheets 15.

Window openings 16 cut in the flap 12 adjacent the hinged edges thereof are adapted to expose the legend "Full" on the flaps 11, when the box is packed, and sold to the retailer.

A number of boxes are adapted to be 75 stacked one upon the other on a shelf or other suitable support, and means must be provided for preventing crushing of the relatively fragile boxes by the weight of the sandpaper above them.

This means has been illustrated as comprising a bracing member formed of a single length of corrugated paper-board or the like 80 17. The intermediate portion of this board lies against the upper inner face of the box 10, and the ends 17^a of the board are turned 85 downwardly, being of a length equal to the height of the box 10 whereby the ends 17^a serve as posts or struts bracing the substantially rigid bridge member 17, and crushing 90 downward strains on the box are sustained by the reinforcement.

Preferably the free lower corners of the tabs 11 bear the legend "Full" and the tabs are rendered detachable by the lines of perforations 11^a above mentioned so that after the 95 box has been emplaced on the shelf, flap 12 may be folded down and the legend-bearing tabs 11 torn off, whereby a visible indication of the number of sheets remaining in any box may be had at all times through the windows 100 16.

The boxes constructed as above described are not only inexpensive, but serve as efficient dispensing containers, affording at all times a visual observation to the storekeeper of the amount of stock which remains. The boxes also may occupy a small amount of space on the shelves inasmuch as they may be stacked 105

directly one upon the other without danger of crushing, and access may thus be had to any of the series of boxes by simply grasping the tab 14 and pulling down the flap 12.

5 Obviously various changes and alterations might be made in the general form and arrangement of the parts described without departing from the invention. Hence I do not wish to limit myself to the details set forth, 10 but shall consider myself at liberty to make such changes and alterations as fairly fall within the spirit and scope of the appended claim.

I claim:

A cardboard box of the class described including an end closure flap having windows arranged in its lower edge, said flap adapted to be opened to permit withdrawal of sheet material through the end of the box, and detachable legend bearing side tabs folding inwardly under the end flap, said windows adapted to visually indicate the quantity of sheet material stacked in the box when the box is laid on its side subsequent to the detachment of the legend bearing tabs. 15 20
